CLAIM

The ornamental design for a dishwasher accessory, as shown and described.

DESCRIPTION

FIG. 1 is a front perspective view of a dishwasher accessory according to a first embodiment showing my new ornamental design where the dishwasher accessory is shown in a position when it is attached to a dishwasher rack;

FIG. 2 is a front view thereof, with the rear view being identical;

FIG. 3 is a top view thereof;

FIG. 4 is a bottom view thereof;

FIG. 5 is a left side view thereof with the right side view thereof being a minor image thereof;

FIG. 6 is a front perspective view of a dishwasher accessory according to a second embodiment showing my new ornamental design where the dishwasher accessory is shown in a position when it is attached to a dishwasher rack;

FIG. 7 is a front view thereof, with the rear view being identical;

FIG. 8 is a top view thereof;

FIG. 9 is a bottom view thereof; and,

FIG. 10 is a left side view thereof with the right side view thereof being a minor image thereof.

The broken lines show surrounding structure or environment and do not form part of the claimed design.

In the embodiments of FIGS. 1-5 and 6-10, the claws may be elastically deformed by expansion or by compression (squeezing) so as to assume a final or assembled configuration that is shown in those figures.
